UNITED STATES PATENT OFFICE.

EMMET A. BROMLEY, OF BRIGHTON, COLORADO.

RESERVOIR OUTLET-VALVE.

SPECIFICATION forming part of Letters Patent No. 679,940, dated August 6, 1901.

Application filed January 4, 1901. Serial No. 42,092. (No model.)

To all whom it may concern:

Be it known that I, EMMET A. BROMLEY, a citizen of the United States of America, residing at Brighton, in the county of Arapahoe and State of Colorado, have invented certain new and useful Improvements in Reservoir Outlet-Valves; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in discharge or outlet valves for water-storage reservoirs; and the objects of my invention are, first, to provide a simple and cheap valve that will not easily get out of order, and, second, to provide a valve and valve-seat that are easy of access. I attain these objects by the mechanism illustrated in the accompanying drawings, in which—

25 Figure 1 is a side elevation, partially in section, of my improved reservoir outlet-valve, showing its application to a body of water in a reservoir; and Fig. 2 is an end elevation of Fig. 1 in the direction of the arrow A.

Similar figures of reference refer to similar 30 parts throughout both views.

Referring to the drawings, the numeral 1 designates the dam of a reservoir for a body of water 2.

3 designates a projecting layer or foundation of rock or timber, as preferred, which forms a foundation for my valve to rest on.

4 designates a platform extending from the top of the dam over the valve, and 5 is a vertical support from the bottom of the reservoir to the outer end of the platform.

Upon the foundation 3 I preferably bolt by bolts 3^a a sleeper 6, which may consist of a wide timber or a block of stone, upon which I rest a T-shaped casting 7 and may use and do use, preferably where the capacity of outflow is not too great, the cast-iron T-pipe fitting in common use, which has its opposite ends threaded. One of these ends I close with a threaded plug 8, which is screwed 45 tightly into it; but where a discharge-valve is required larger than the cast-iron T-pipe fittings in use a special pattern is made and

one end can be made solid and the plug 8 dispensed with. The T-valve body is arranged with its open end facing the dam. A pipe 9 is threaded to this end and extends through and is built in the dam and conveys the water from the reservoir and valve through the dam. One side of the T-valve body is provided with the usual projecting hollow hub 10, which forms a side opening into the body of the T. I bore the shell of this opening into a semicircular seat 11. I arrange the T-valve body upon its foundation with its semicircular valve-seat standing in a vertical plane and secure it to its foundation-block by strap-bolts 12, which I place over each end. Around the hub at equidistances apart I place vertical standards 13, four or more being preferably used. These are bent at 70 their lower ends to fit over the round projecting annulus at the end of the hub and down the sides of the hub. Their ends are then secured to the hub by two semicircular straps 13^a, that are formed to fit around the hub and 75 that are bolted together around the hub at their opposite ends. These vertical supports preferably extend up to and against the under side of the platform, to which they are secured by bolts 14 and form guide-rods for guiding 80 the valve to its seat. Around these standards I place a strong wire-netting 15, which keeps driftwood and grasses and fish from entering the valve. On the valve-seat of the T-pipe I place a valve 16, which consists of a round 85 casting having an eye 17 in its upper end and a rounded end at its opposite end fitting in the valve-seat of the T-pipe. Instead, however, of making the valve-seat end of the valve solid I preferably arrange and secure 90 a rounded piece of rubber or some other suitable material 18 to it by a bolt 19, which extends up through the rubber and threads into the valve-casting.

This valve can be made as heavy as desired; but it should be made heavy enough to seat tightly against the seat in the T-pipe.

To the eye in the top of the valve I secure one end of a rod 20 by a ring formed at its end. This rod extends loosely up through the platform and a sleeve 21, that is bolted to the platform, and acts as a guide for the rod. The opposite end of the rod 20 is pivotally secured by a bolt 22 to a slot 23, formed in one end

of a lever 23^A. This lever is pivoted by a bolt 24 to a standard 25, secured to the top of the platform, and the opposite end of the lever extends beyond this standard and forms the handle end of the lever. A standard 26 is erected close to it, which is provided with holes 27 at different predetermined distances apart, to which the handle portion of the lever can be secured by a bolt 28, which is extended through and beyond the lever far enough to pass through and be bolted to the standard. By this arrangement the handle of the lever can be tipped on its pivotal bolt 24 and raise or lower the valve through the medium of the rod 20 from or to its seat in the T-pipe, and the handle can be secured in any one of the holes in the standard and the valve raised and lowered and set at any predetermined distance desired.

20 In order to set the valve so that it can be raised a predetermined distance and then be closed intermittently, I thread the rod 20 and thread two check-nuts 29 and 30 on it, placing them on the rod before the lower ring is formed in its lower end and place a large hand-hole 31 in the platform close to the sleeve, through which they are adjusted and set. These nuts are adapted to strike against the bottom of the platform. By this means 30 the valve can be raised a predetermined distance and an amount of water can be run through the valve during a period of so many hours each day or at intervals and then the valve can be closed. In addition a suitable 35 bolt 32 and a padlock 28^A can be passed through this rod and sleeve or to any of the other parts of the valve's rods to securely lock it either closed or open.

My invention is essentially adapted for irrigation reservoirs and ditches and is simple and inexpensive.

Having described my invention, what I claim as new, and desire to secure by Letters Patent, is—

45 1. In a valve for reservoirs, the combination of a T-pipe-shaped valve-body portion having a side entrance between its ends and a semicircular valve-seat at said entrance, and having one of its ends closed and a discharge-pipe threaded to and leading from the opposite end, a valve comprising a piece of 50 metal provided with a rounded end fitting the semicircular seat in said T-pipe, a rod

pivotaly connected to the upper end of said valve and means including a rocking lever 55 connected to the upper end of said rod for raising and lowering said valve, substantially as described.

2. In a reservoir-valve the combination of the T-shaped valve-body having a side entrance, an open semicircular valve-seat in said entrance, a valve comprising a plug-shaped casting having a rounded seat at one end adapted to fit said semicircular valve-seat in said T-shaped body portion, a rod pivoted to the upper end of said valve, means including a rocking lever for raising and lowering said valve from and to said seat, a thread on said rod and check-nuts threaded thereto, and arranged to adjust and set the 70 vertical movement of said valve, vertical guide-rods extending upward around said valve, a wire-netting around said rods and the discharge-pipe leading from said T-pipe and valve, substantially as described. 75

3. In a reservoir-valve, the combination of the T-valve body, the valve, the rod threaded at one end and pivoted to the top of the valve, the sleeve, the standards, the handle-lever pivoted to said rod and to one of said standards, the check-nuts and the discharge-pipe leading from said T-pipe, substantially as described. 80

4. In a reservoir-valve, the combination of the T-pipe having an open valve-seat, the 85 valve having an end fitting said valve-seat, the rod threaded at one end and containing nuts and pivoted to the top of the said valve, the handle-lever pivoted to said rod, the standards for supporting said handle-rod, the 90 valve's vertical guide-rods, the semicircular straps arranged to clamp them to the T-pipe, the screen surrounding said guide-rods, the sleeve guiding said valve-rod, the lock through said sleeve and rod, the dam, the 95 platform extending from said dam over said valve and connected to said valve's vertical guide-rods and the discharge-pipe leading from said T-pipe through said dam, substantially as described. 100

In testimony whereof I affix my signature in presence of two witnesses.

EMMET A. BROMLEY.
